UNITED STATES PATENT OFFICE.

LEON BLOCH, OF SAN FRANCISCO, CALIFORNIA.

DESIGN FOR A VEHICLE-LAMP AND REFLECTOR.

41,347.

Specification for Design.

Patented May 2, 1911.

Application filed December 23, 1910. Serial No. 599,056. Term of patent 7 years.

To all whom it may concern:

Be it known that I, LEON BLOCH, a citizen of the United States, residing at San Francisco, in the county of San Francisco and State of California, have invented a new, original, and ornamental Design for a Vehicle-Lamp and Reflector, of which the following is a specification, reference being had to the accompanying drawing, forming part thereof.

Figure 1 is a front view and Fig. 2 a plan view of a vehicle lamp and reflector, showing my new design.

I claim:

The ornamental design for a vehicle lamp and reflector, as shown.

LEON BLOCH.
